GUN SHELL FEEDING MECHANISM

Sigmund Schiff, Cincinnati, Ohio, assignor to the
United States of America as represented by the
Secretary of War

Application December 18, 1945, Serial No. 635,818

31 Claims. (Cl. 89—33)

(Granted under Title 35, U. S. Code (1952),
sec. 266)

1

The invention described herein may be manufactured and used by or for the Government for governmental purposes, without the payment to me of any royalty thereon.

This invention relates to a gun and more particularly to a heavy caliber gun capable of operation as an automatic or preferably semiautomatic weapon specifically adapted for use in aircraft, land vehicles, or vessels.

The present invention finds its greatest utility and application in connection with its use as an aircraft cannon. Weapons of this type recently mounted in aircraft are of relatively heavy caliber, such as 75 mm. to 105 mm. In the mounting and operation of a weapon mounted in an airplane of the pursuit type, it is desirable that the operation of the weapon be either completely automatic or semiautomatic so that it may be easily and simply fired by the airplane pilot. This general requirement is also applicable to the use of the weapon in land vehicles or small boats.

In order that a weapon may be completely or semiautomatic, it must be automatically loaded and otherwise automatically conditioned for firing. To this end, it is desirable that the various components of the weapon be appropriately coordinated, due regard being had to simplicity of construction and safety of the operator and of the weapon itself. It is therefore found desirable to coordinate the components of the gun in such a manner that various phases of its operation are conditioned upon successful completion of related phases of its operation.

It is a principal object of the invention to utilize the power generated by the gun in recoil to operate the feeding and loading mechanism.

The invention has for another important object the provision of control mechanism interconnected with the firing control means for the gun so that the firing control means will be inoperative to fire the gun unless the feeding and loading mechanisms have satisfactorily completed their cycles of operation.

Other objects of the invention are to provide means for detecting the return or nonreturn of the gun to battery after it has been fired and recoiled; to provide means for detecting the presence or absence of a shell in the chamber of the gun; to provide means for detecting failure of the breech of the gun to close; to provide—in conjunction with shell-delivery means that moves from a position remote from the gun to a position to the rear of the breech of the gun—means for precluding firing, and conse-

2

quently recoil, of the gun until the shell-delivery means is clear of the path of recoil of the gun; to provide—in conjunction with a rammer for chambering shells—means for precluding ramming or chambering of a shell while a complete round or shell case remains in the breech of the gun or while the breech is closed; to provide control means, specifically electrical, coordinating the various phases of operation of the gun and feeding and loading means so that a continuous cycle of operation is insured; and to include in this control mechanism control elements rendering operation of the weapon as simple and as safe as is practically possible.

The foregoing and other desirable objects and important features of the invention will become apparent to those skilled in the art as the disclosure is more fully made in the following detailed description of a preferred embodiment of the invention as illustrated in the accompanying sheets of drawings in which:

Fig. 1 is a perspective view of the weapon and the principal component parts thereof;

Fig. 2 is a plan view of the structure shown in Fig. 1, with the rearward position of the rammer illustrated in broken lines;

Fig. 3 is an enlarged fragmentary end elevation of the rear or breech end of the weapon, certain parts of the supporting structure being illustrated in broken lines;

Fig. 4 is an enlarged fragmentary front elevational view of the lower portion of the shell-carrying and shell-feeding mechanism;

Fig. 5 is a longitudinal fragmentary sectional view of a portion of the breech structure of the gun showing the details of construction of the means for detecting whether a shell is present in or absent from the chamber of the gun, whether the breech is open or closed, and whether the gun has succeeded or failed to return to battery;

Figs. 6, 7, 8 and 9 are diagrammatic illustrations of the electrical circuits embodied in the control and coordination of the phases of operation of the weapon, the views being so drawn that the active circuits are illustrated in full lines and the inactive circuits in dotted lines;

Fig. 10 is a diagrammatic illustration of the breechward end of the gun showing the various positions occupied by the rammer arm of the rammer mechanism; and

Fig. 11 is a view of the left-hand rear portion of the tube-and-breech assembly illustrating the position of the means thereon for actuating the shell-feeding mechanism.

Although reference to the invention so far has

been in terms of its use as an automatic or semi-automatic weapon having particular adaptability to aircraft, it should be understood that the invention has similar utility in other instances, such as those heretofore mentioned, and even under conditions in which the weapon is emplaced or otherwise fixedly mounted. Accordingly, the following detailed description should be taken as illustrative and not limiting.

The major components of the invention are best illustrated in Fig. 1, wherein it is shown that a gun mount 20 is provided with supporting trunnions 21 (only one of which is shown) on which is carried a recoiling gun designated generally by the numeral 22. The particular gun herein shown is of the type having concentric recoil mechanism, an example of which is shown and described in the United States patent to Lucht, No. 2,358,340. The gun in this patent is shown as comprising an outer cylindrical sleeve or cradle 23 within which is concentrically contained the recoiling tube-and-breach assembly. The recoil mechanism for the gun is contained in the annular space between the cradle and the tube 24.

In the present instance, the cradle is carried on the trunnion supports 21 journaled in bearings carried by the gun mount 20. The gun tube is shown at 24 and includes at its rear or breechward end a breech ring 25, within which is carried a breechblock 26. The breech assembly chosen for purposes of illustration is of the type in which the breechblock moves vertically in opening and closing. For the purposes of the present description the particular breech structure is of relatively minor importance and it will be understood that any conventional breech structure may be employed in the practice of the invention. Consequently, the specific details of construction and operation of the mechanism for controlling the breechblock have been omitted.

The rearward portion of the cradle 23 includes a frame extension 27 having a depending support 27a by means of which the cradle is rigidly secured to the base of the mount 20. The construction just referred to provides for a rigid mounting of the gun 22 on the mount 20 so that no elevation and depression of the gun is possible. However, elevation and depression of the gun is not desired in the instance in which the gun is mounted in an airplane, for the gun is aimed by aiming the plane. It will be understood, of course, that in the various applications of the invention to other situations, the gun mount may be appropriately modified to meet the circumstances.

The upper portion of the rear frame or support extension 27 provides means for the mounting of a longitudinally extending rammer or loader housing indicated generally by the numeral 28, the rearward or breechward portion of which includes a pair of depending attaching flanges 29 by means of which the housing 28 is rigidly carried on the extension 27 and is fixed with respect to the mount so that it does not move during recoil and counterrecoil of the gun.

The particular type of rammer chosen for the purposes of illustration herein is that disclosed and claimed in my copending application, Serial No. 635,817, filed December 18, 1945, now Patent Number 2,520,966. As shown in this application, the rammer comprises a longitudinally reciprocable rammer tube or shaft carried in a housing support on a gun mount and having at its rear-

ward end a rammer arm adapted to engage individual rounds of ammunition and to ram such rounds successively into the breech chamber of the gun. It is also illustrated in my said application that the rammer is moved from a forward position out of the path of the recoiling tube-and-breach assembly, to a rearward position in which the rammer arm is disposed generally in axial alignment with the bore of the gun. The means for moving the rammer rearwardly comprises a connection to the tube-and-breach assembly so that the power generated by the recoiling gun is utilized to operate the rammer; compression springs are loaded upon rearward movement of the rammer for reaction when released to return the rammer, with a round of ammunition, to its forward position so that the round is delivered or chambered in the gun tube.

There has been illustrated in connection with the present invention only so much of the aforesaid rammer as is necessary to an understanding of the present invention and its inclusion of such rammer as a component thereof. The reciprocable rammer member is indicated by the numeral 30 and the rammer arm is designated at 31. A coaxial extension housing 32 at the forward end of the rammer housing 28 contains the compression springs for returning the rammer to its forward position. The supporting housing 28 is provided at its upper portion with a rectangular track, indicated generally at 33, comprising a pair of longitudinal slits or grooves cross connected at their opposite ends by transverse open portions constituting transverse grooves. The rammer member 30 is provided at an intermediate upper portion thereof with an upstanding pin 34 (Fig. 2) which projects upwardly from the rammer and through the slits or grooves of the track 33 and which, during the operation of the rammer, follows the rectangular track 33 to guide the rammer 30 longitudinally and to guide the rammer arm 31 transversely of the direction of travel of the rammer member. When the rammer is in its forward position, the pin 34 is at the forward or counterrecoil end of the right-hand longitudinal groove of the track 33 (as viewed from the breech of the gun) and the rammer arm 31 is disposed in an upper position spaced above the axis of the bore of the gun. When the rammer moves rearwardly, the pin 34 moves along and to the rear of the track 33 where a torsion spring (not shown) rocks the rammer member about its longitudinal axis to move the rammer arm toward a position in which the inner end thereof is generally coaxial with the bore of the gun (Fig. 10).

The rearward portion of the rammer housing 28, above the attaching flanges 29, is provided with a pair of upstanding ears 35 on which is pivoted a latch 36 under the control of suitable control means, herein illustrated as a solenoid 37, mounted on a bracket 38 formed as part of, or secured to, the rammer housing 28. The connection between the tube-and-breach assembly 24-26 and the rammer member 30 is best shown in Fig. 2, wherein it is illustrated that the breech ring 25 has rigidly secured thereto a driving plate 39 extending laterally outwardly from the breech ring and having an opening (not shown) through which the rammer arm 30 passes. The member 30 carries thereon a cylindrical buffer housing 40, positioned with respect to the driving plate 39 to be engaged by the driving plate as the gun recoils. The housing 40 contains suitable buffering

mechanism, not necessary to an understanding of the present invention and therefore not shown. When the rammer 30 is driven rearwardly by recoil of the gun, the pin 34 on the intermediate portion of the longitudinal rammer member reaches the rearward end of the track 33 and is engaged by the rear cutout portion of the latch 36. The rammer is thus retained in its rearward position (broken lines in Fig. 2) with the rammer arm in the intermediate position shown in Fig. 10, and is conditioned for release to ram or chamber a round of ammunition when the solenoid 37 is energized to release the latch 36 and allow the rammer to move forwardly by means of reaction of the compression springs contained in the extension housing 32 on the rammer housing 28.

In my copending application, Serial No. 635,819, filed December 18, 1945, now Patent Number 2,604,820, I have disclosed a shell-feeding mechanism that I have found to be suitable for use as a component of my automatic weapon shown herein. Reference is had to said application for details of construction and operation, in addition to those contained in the present description.

As best shown in Fig. 1, the shell-feeding mechanism comprises a rigid unitary supporting structure indicated generally by the numeral 45, rigidly carried at its lower portion on a longitudinally extending supporting tube 46. This tube is mounted at its opposite ends on vertical supporting brackets 47, which serve as means by which the feeding mechanism may be mounted in proximity to the gun to form a compact unit therewith. As illustrated in Fig. 1, the brackets 47 may be mounted on the floor of an airplane fuselage, such as is indicated at 48, or to any other suitable supporting structure. The gun mount 20 is likewise secured to the floor 48.

The supporting structure 45 includes a longitudinal vertical web portion 49 by means of which the feeding mechanism may be additionally supported on the wall of an airplane fuselage, for example. The supporting structure 45 is provided with front and rear, upright, semicylindrical casings 50 and 51. The front casing 50 is provided at upper and lower portions thereof with bearings which journal the opposite ends of a spiral feed member such as a feed screw 52. The rear upright casing 51 similarly supports a similar feed screw 53. As best shown in Fig. 3, each casing embraces substantially half of its feed screw and the other half of the screw is available at the inner side of the supporting structure 45 to form, in effect, a plurality of vertically spaced pockets in which are carried a series of rounds of ammunition such as shells 54, Fig. 3. The upper end of the supporting structure 45 is provided with a pair of longitudinally spaced outwardly directed brackets 55 which rigidly support the opposite ends of a longitudinally extending bar 56. Lower portions of the supporting structure 45 are provided with similar brackets 57 which carry a similar bar 58. The bars 56 and 58 are rigidly cross connected by a pair of vertical, longitudinally spaced guide members 59 which, as best shown in Figs. 1 and 3, respectively parallel the feed screws 52 and 53 and are spaced outwardly therefrom to complete the means for the supporting of the series of shells 54. Each of the guide members 59 is curved upwardly and outwardly at its upper end to provide in conjunction with the feed screws 52 and 53, an enlarged space through which

the shells 54 may be individually loaded into the feed screws.

The feed screw 52 is provided at its upper end with a vertical stub shaft which extends into a housing 60 positioned at the top of the casing 50. Thus housing contains suitable bevel gearing (not shown) by means of which the feed screw 52 may be rotated by a horizontal shaft 61, the forward end of which is contained within the housing 60. The rearward end of the shaft 61 is contained in a housing 62 carried by the upright casing 51. This housing is similar to the housing 60 and contains suitable gearing (not shown) for connecting the shaft 61 to a vertical stub shaft extension at the upper end of the feed screw 53. A crank 63 is suitably connected with the gearing in the housing 62 and provides means by which the feed screws 52 and 53 may be manually rotated, which is necessary when the shells 54 are initially loaded into the feeding mechanism. The feed screws have oppositely wound helices and the connection between them and the shaft 61 and gearing in the housings 60 and 62 is such that the feed screws rotate in opposite directions, thus restraining the shells 54 against tendency to endwise displacement in either direction. In order that the shells 54 may be properly aligned, guided and retained in the feeding mechanism, there is provided at the rearward end of the supporting structure 45 a vertically extending grooved guide 64 positioned to engage the inner portions of the rims of the shells 54.

The longitudinal supporting tube 46 carries rockably thereon, intermediate the upright casings 50 and 51, a driving cam 65, positioned with respect to the gun 22 to be engaged upon recoil of the tube-and-breech assembly 24-26 by a driving lug or member 66 (Figures 3 and 11) carried at the inner or left side of the breech ring 25 (Fig. 11). Just rearwardly of the driving cam 65, the supporting tube 46 carries rigidly thereon a support 67 having an upper hollow cylindrical housing 68, preferably formed integral therewith and disposed on an axis transverse to the supporting tube 46. As disclosed in my copending application, Serial No. 635,819, filed December 18, 1945, referred to above, the cylindrical bore in the housing 68 contains a powerful compression spring arranged to be loaded by means connected to the driving cam 65. As shown herein, this means includes a plunger 69 mounted for reciprocation in the housing 68 and having oppositely extending trunnions 70 and 71 which project respectively through slots 72 in opposite side portions of the housing 68. The compression spring contained within the cylindrical housing portion 68 is indicated by the numeral 73 and may be seen through the rear slot 72 in the housing 68 in Fig. 3. The trunnion 71 extends forwardly through the slot 72 in that side of the housing 68 and is connected by means of a short link 74 and pin 75 (Fig. 3) to the upper end of an arm 76 rigidly connected to, or formed as part of, the rearward portion of the driving cam 65. Consequently, as the driving cam 65 is rocked upwardly on the tubular support 46, the arm 76 will be swung in a counterclockwise direction (as viewed from the breech end of the weapon) and will move the plunger 69 to the left (as viewed in Fig. 3), thus compressing the spring 73 within the housing 68.

The upper portion of the housing 68 is provided with a slot transversely thereof through which a latch 77 may extend into the housing

68 to retain the plunger 69 in position with the spring 73 compressed. The latch 71 is pivoted at 73 on one of a pair of ears 79 formed integral with and extending upwardly from the housing 68. A tension spring 80 serves to maintain the latch 71 in latching position behind the plunger 69. When the latch is released, as will hereinafter appear, to allow the plunger to return to its starting position at the right-hand side of the cylindrical housing 68, the lower portion of the latch rests on the upper portion of the plunger. In other words, the latch 71 is permitted to pass through the slotted upper portion of the cylindrical housing 68 only when the plunger 69 is moved to the position in which the spring 73 is compressed.

The trunnion 72 extends rearwardly through the slot 72 in that side of the housing 68 and is pivotally connected to one end of a driving link 81 (Figs. 3 and 4). The other end of the link 81 is pivotally connected by means of a pin 82 to the upper end of an inwardly and downwardly curving link 83, the lower end of which is pivotally carried on a longitudinal pin 84 mounted in a pair of longitudinally spaced, laterally extending ears 85 at the lower end of and preferably formed integral with the rear upright casing 51. The link 81 is provided at its opposite ends with slots 86 and 87 (Fig. 3) which cooperate with the pins 70 and 82, respectively, to provide for necessary lost motion in the linkage during operation of the feeding mechanism, the detailed functioning of which will be set forth below.

As best shown in Fig. 4, the upper end of the curved link 83 is bifurcated to form a pair of transversely spaced mounting lugs 88 between which is disposed the lower end of an upwardly extending feed-screw-driving link 89. The pin 82, previously described as forming the pivotal connection between the driving link 81 and the curved link 83, extends through the mounting lugs 88 and through the lower end of the link 89, thus forming a pivotal connection between the curved link 83 and the feed-screw-driving link 89. The upper end of the link 89 is bifurcated to form a pair of integral spaced arms 90 which receive pivotally therein opposite trunnions 91 of a sliding member 92. The member 92 is carried for vertical reciprocation on a vertical shaft 93, the lower end of which is journaled in a bearing 94 at a lower portion of the rear upright casing 51, and the upper portion of which is journaled in an upper bearing 95 (Fig. 4) positioned on the rear upright casing 51 just below the lower end of the rear feed screw 53, at which point the shaft 93 is connected to the feed screw 53 for rotation therewith. The shaft 93 is provided with a longitudinally extending straight groove 96; in addition, this shaft is formed with a spiral groove 97 which makes one complete turn about the shaft 93 from a point beginning at an intersection with the straight groove 96, about one-third of the distance from the lower end of the shaft 93, to a point at the upper end of the shaft (Figs. 3 and 4). The sliding member 92 is provided with a spring-pressed follower 98 which extends within the sliding member and engages either of the grooves 96 or 97, depending upon whether the sliding member is moved upwardly or downwardly on the shaft 93.

When the parts are in the position shown in Figs. 3 and 4, that is with the sliding member 92 at the upper end of the shaft 93, these parts

are conditioned for downward movement, in which case the follower 98 of the sliding member 92 follows the straight groove 96 in the shaft 93. This movement of the sliding member 92 has no effect on the shaft; that is, the shaft is not rotated during the downward travel of the sliding member 92. However, as will hereinafter more fully appear, as the sliding member 92 is moved upwardly on the shaft 93, the follower 98 is caused to engage the spiral groove 97 in the shaft, thus effecting one complete revolution of the shaft and consequently rotating the feed screw 53 through one revolution; because of the driving connection between the feed screws 52 and 53—comprising the shaft 61 and gearing in the housings 60 and 62—the feed screws 52 and 53 are simultaneously rotated, but in opposite directions.

As best shown in Figs. 2 and 3, each upright casing 50 and 51 rigidly carries thereon at laterally extending bearing bracket 99 in which is journaled the opposite ends of a longitudinally extending rockshaft 100. This rockshaft rigidly carries thereon, between the bearings 99, a pair of longitudinally spaced tray arms 101, each of which, as best shown in Fig. 3, extends laterally from the rockshaft in the form of a reversely bent S. The inner or free end of each arm is of semi-circular configuration formed about a radius equal to that of the size of shell carried by the feed screws and forms a cradle portion 102 within which individual shells are carried as the arms move together from their position shown in Fig. 3 to a position in which the shell carried thereby is in position to be received and rammed or chambered by the rammer 30. The cradle portions of the tray arms 101 are rigidly cross connected by a pair of longitudinally extending strip members 103, each of which is provided at its rear end with a retaining clip 104 adapted to limit endwise displacement of the shells carried in the tray structure provided by the arms 102 and strip members 103. Each tray arm is provided at a portion thereof, adjacent its cradle portion 102, with a short shaft or pin 105 (Figs. 3 and 4) disposed on a longitudinal axis. Each pin has pivotally mounted thereon a bell crank 106, one arm of each of which forms a retaining arm 107, and the other arm of each of which forms a control arm 108 having a guide or control pin 108a. The retaining arm 107 of each bell crank 106 carries rotatably thereon a roller 109 (Fig. 3) mounted on an axis normal to the axis of the mounting of the bell crank on the pin or shaft 105. Each bell crank 106 is normally resiliently urged in a direction such that the retaining roller 109 thereon engages the periphery of a shell in the cradle portion 102, the means for accomplishing this purpose consisting of a tension spring 110 connected at one end to a pin 111 on the tray arm 101 and at its other end to a depending ear 112 adjacent the fulcrum point of the bell crank.

The pivot pin 82 forming the driving connection between the driving link 81, the curved link 83 and the feed-screw-driving link 89 serves also as a pivotal mounting for the lower end of an upwardly extending tray-driving link 113. As best shown in Figs. 3 and 4, the lower end of the tray-driving link 113 is carried on the pin 82 between the driving link 81 and the forward side of the curved arm 83. The upper end of the tray-driving link 113 is pivotally connected to the rear tray arm 101 by means of the short shaft 75 or pin 105 on which the bell crank 106 is mounted.

Part of the automatic control of the weapon herein set forth consists of means for controlling movement of the tray between its two positions. For this purpose the rockshaft 100 carries rigidly thereon, intermediate the tray arms 101, suitable control means in the form of a tray solenoid 114 having an extensible plunger 115 provided with a collar 116 which engages a yoke 117 on the lower bifurcated end of a rockable arm 118. The arm 118 is pivoted on a pin 119 on a pair of ears mounted on the rear side of the forward tray arm 101. The solenoid plunger 115 is normally spring-pressed by a compression spring 120 to the position shown in Fig. 4. The upper end of the lever arm 118 is bifurcated and embraces a collar 121 rigidly secured to a longitudinally extending release bar 122, the opposite ends of which are preferably square in cross-section (Fig. 3) and are slidably carried respectively in the tray arms 101. The arrangement is such that extension of the solenoid plunger 115, upon energizing of the solenoid 114, will move the release bar 122 rearwardly, or to the left, as viewed in Fig. 4. The forward or right hand end of the release bar extends forwardly through the forward tray arm 101 for engagement with locking means, to be presently described.

The forward upright casing 58 is provided at its rear face with a triangular bracket 123 provided at its rear face with an upper catch or lug 124 and a lower catch or lug 125. The lower portion of the bracket 123 is directed horizontally rearwardly and is provided with a buffer 126, of any suitable resilient material, which serves as a stop to limit downward travel of the tray arms 101. The upper or outer end of the bracket 123 is provided with a rearward extension on which is mounted a similar buffer element 127 (Fig. 3) by means of which upward travel of the tray arms 101 is limited. The release bar 40 122 carries rigidly thereon, adjacent its rearward end and just forwardly of the rear tray arm 101, a depending release arm 128 (Figs. 3 and 4).

Since the solenoid 114 is rigidly carried by the rockshaft 100 on which the tray arms 101 are mounted, downward swinging of the tray arms from the position shown in Fig. 3 to that in which the shell carried by the tray arms is in axial alignment with the bore of the gun 22 will result in a repositioning of the solenoid 114, release bar 122 and release arm 128. Consequently, the lower end of the release arm 128 will be redispersed from the position shown in Fig. 4 to a position in which it is in alignment with the upper end of the latch 77 (previously described as being pivotally mounted on the top of the cylindrical housing 68). Hence, the single solenoid 114 is capable of the double function of releasing the forward end of the release bar 122 from the upper catch 124, when the tray is in its upper position and of pivoting the latch 77 by means of the release arm 128 when the tray is in its lower position. When the tray moves to its lower position, the release bar 122 engages the lower catch 125 on the bracket 123 and thus prevents the tray from bouncing or otherwise moving accidentally upwardly. At the same time that the solenoid 114 functions to release the latch 77 it also releases the release bar 122 from the lower catch 125. Thus, the release of the release bar 122 from the catch 125 is coordinated with the conditioning of the tray for return movement from its lower position to the position shown in Fig. 3, this movement being effected by reaction of the now re-

leased compression spring 73 in the cylindrical housing 68.

As previously stated, reaction of the spring 73 serves also to drive the sliding member 92 upwardly on the feed screw shaft 93 so that said shaft is rotated by means of engagement between the follower 98 of the sliding member 92 and the spiral groove or track 97 in the shaft.

As heretofore stated, one of the principal objects of the present invention is to provide a simple and efficient means by which the functions of the component parts of the weapon may be controlled and coordinated, with particular emphasis on the desideratum that the components be made to function in proper order or be prevented from operating unless and until previous phases of operation have been accomplished. At the same time, due regard is had to the requirement of simplicity, to the safety of the operator, and to the elimination of the possibility of damage to the weapon because of malfunctioning thereof.

One of the components of the control means provided according to the present invention consists of means for detecting whether the chamber of the tube is empty or whether it has been properly loaded with a shell. This means further accomplishes the function of determining whether the breech has closed or failed to close. And interrelated means is provided for detecting whether or not the gun has returned to battery. As shown in Figs. 3 and 5, the rear end of the gun tube is provided in the usual manner with a chamber 129. Fig. 5 illustrates the positions of the parts when (a) the chamber 129 contains a shell 54, (b) the gun is in battery, and (c) the breechblock 26 is closed.

As best shown in Figs. 2, 3 and 5, the forward portion of the breech ring 25 carries a bracket 130 having a generally horizontal flange 131, secured by bolts 132 to an upper portion of the breech ring 25, and a vertical rectangular sleeve 133. The flange 131 and sleeve 133 are preferably formed as integral parts of the bracket 130. The sleeve 133 is provided with a vertical opening 134 (Fig. 5) within which is carried for vertical reciprocation a feeler 135 provided along its rear side with teeth forming a rack 136. The bracket 131 includes a pair of rearwardly directed flange portions or ears 137 in which is mounted a transverse short shaft 138. This shaft has keyed thereto between the flange portions 137 a pinion 139 meshing with the rack 136. The short shaft 138 extends at opposite sides of the flange portions 137 and has keyed, or otherwise rigidly secured, thereto one end of a swingable arm 140. The upper end of this arm is provided with an outer threaded cylindrical portion 141 within which is adjustably carried a contact control screw 142.

The rearward portion of the cradle 23 has rigidly secured thereto a mounting bracket 143 (Fig. 2) which extends laterally from a point adjacent the rammer housing 28 to a point adjacent the bracket 130. At the latter point the mounting bracket 143 is provided with a vertical attaching flange 144 on which is mounted a pair of electrical switches 145 and 146. The right-hand switch 146 (as viewed from the breech) has an extending contact strip 147 positioned to be engaged or released by the contact control screw 142 on the swingable arm 140. The left hand switch 145 is provided with a contact strip 148 positioned to be engaged or released by a contact control member 149 rigidly carried at the

upper end of an upward extension of the right-hand flange 137 of the bracket 130.

The upper end of the feeler 135 is provided with a forwardly extending lug 150 to which is connected the upper end of a tension spring 151. The lower end of the spring 151 is connected to a pin 152 carried by a pair of ears 153 on the flange 131 at the junction of said flange with the vertical sleeve portion 133. The action of the spring 151 is such as to urge the feeler 135 normally downwardly. However, the presence of the shell 54 in the chamber 129 prevents downward movement of the feeler 135, since an abutting element 154 at the lower end of the feeler abuts an upper portion of the rim of the shell 54 in the chamber 129. The upper forward portion of the breechblock 26 is recessed as at 155 and likewise is abutted by the lower end 154 of the feeler 135 when the breechblock is closed. The function of the construction thus far described is such that when the chamber 129 is empty and the breechblock 26 is open, the electrical switch 145 will be closed, since downward movement of the feeler 135 will cause forward swinging of the arm 140 so that the contact control screw 142 will engage the contact strip 147.

The relationship between the switch 145, with its contact strip 148, and the contact control member 149 is such that the switch 145 is closed when the gun is in battery. It will be noted that the feeler switch 146 also operates or fails to operate on the basis of the return or nonreturn of the gun to battery; that is to say, the feeler switch 146 is carried by the bracket 123 on the cradle 23 which is fixed against recoil; the contact control screw 142 is carried by the arm 140 which is mounted on the bracket 130 which is in turn carried by the breech ring 25. The breech ring, of course, recoils with the tube 24 and, should the parts fail to return to battery, there would be no closing of the feeler switch 146, even though the chamber 129 contained no shell and even though the breechblock 26 was closed, since the contact control screw 142 could not engage the contacting strip 147 of the feeler switch 146. There is thus provided a double safeguard against any malfunctioning of the weapon incident to failure of the gun to return to battery.

The delivery of shells by the tray to a position to be received by the rammer is likewise coordinated with the other functions of the weapon. The control and timing mechanism in this respect is also electrical and, as will hereinafter appear, is appropriately related to the breech and feeler switches 145 and 146.

The triangular bracket 123 at the rear side of the front upright casing 50 is provided with a lower tray switch 156. As shown in Figs. 3 and 4, this switch is mounted on that portion of the bracket 123 that carries the lower buffer 126. The switch 156 is of the double throw type and includes first and second contacts 157 and 158 and a spring-pressed contact control plunger 159. As shown in Figs. 6 to 9, the contact 157 is connected in series with the tray solenoid 114 by a lead 160 and the contact 158 is connected by a lead 161 to the rammer solenoid 37.

The contact control plunger 159 is connected by a lead 162 with the contact strip 147 of the cartridge feeler switch 146. When the tray is in its upper position ready to receive a shell 54 from the feed screws 52 and 53, there is no engagement between the forward tray arm 101 and the plunger 159, and the latter is thus released for outward movement by spring pressure to make

an electrical connection with the contact 157 of the switch 156 (Figs. 6 and 7). When the tray moves to its lower or delivery position, the plunger 159 of the switch 156 is engaged by the forward tray arm 101 and is depressed to make an electrical connection with the contact 158 of the switch 156 (Figs. 8 and 9).

The bracket 123 on the front upright casing 50 carries a second or upper tray switch 163. This switch is mounted on that portion of the bracket 123 that carries the upper buffer 127. As shown in Figs. 6 to 9, the switch 163 includes a contact control plunger 164 engageable with either a first contact 165 or a second contact 166. The contact 165 is connected with the tray solenoid 114 by a short lead 167 connected to the lead 160. A suitable lead 168 connects the contact 166 of the switch 163 in series with a firing control switch 169, which is in turn connected in series with a firing actuator 170. The latter element is suitably connected to the firing mechanism of the gun 22 and may be of any conventional construction. The structure has therefore been illustrated only diagrammatically in the drawings. When the tray is in its upper or shell-receiving position (Fig. 3), the plunger 164 of the switch 163 is depressed to make an electrical connection with the contact 166 (Fig. 6). A signal light 171 is connected in series with the contact 166 and in parallel with the firing switch 169 and, as will hereinafter appear, will be illuminated when the firing circuit is completed up to the firing switch. The plunger 164 is connected by a lead 172 to the breech switch 145.

In addition to control and coordination of the functions of the weapon in firing, recoil, and shell-delivery, the control mechanism provided by the invention includes also control and coordination of the ramming phase. For this purpose the control system is provided with a control switch 173 which is controlled by the rammer and which is carried in part by the rammer buffer 40 and in part by the rammer housing 28. The switch 173 is of the double throw type and includes a first contact 174 connected in series by a lead 175 with the cartridge feeler switch 146 and a second contact 176 connected by a lead 177 in series with the breech switch 145. The rammer switch 173 further includes a contact control plunger 178 which is connectable with either contact 174 or 176. The plunger 178 is connected by an electrical conduit 179 to a source of electrical energy shown diagrammatically and designated at 180 in the drawings. A control member 181 is carried by the rammer on the buffer 40 thereof. The switch body 173 is carried on the rammer housing 28. As will appear from Fig. 2, the control member 181 is adapted to depress or release the spring-pressed plunger 178, depending upon whether the rammer is in forward or chambering position or in rearward or shell-receiving position.

OPERATION

The operation of the weapon consists of a main cycle involving the subordinate cycles of firing, recoil, counterrecoil, shell-delivery, ramming or chambering of a shell by the rammer, and return of the shell-delivery means to advance another shell for the next main cycle. As stated above, the electrical control circuit and the various branches thereof coordinate these subcycles or phases of operation of the weapon. Due regard is had to the provision of means for preventing certain phases of operation of the weapon in the event of malfunctioning of the weapon in

any other phase. For the sake of clarity, the following description of the operation of the weapon will be divided into four main phases in each of which the functioning of the mechanical components of the weapon will be described in connection with the electrical control thereof; viz., (I) firing, (II) shell-delivery, (III) ramming, and (IV) shell-advance.

Firing (Fig. 6)

In the description of this phase of the operation of the weapon, it will be assumed that the weapon has been loaded manually and is otherwise in condition for firing. The following conditions are necessary to the firing of the weapon and it will be assumed that these conditions have been established: (a) the tray is up (Fig. 3); (b) the gun is in battery; and (c) the rammer is forward in its position as shown in full lines in Fig. 2. When these conditions are met, the circuit will be complete from the source of energy 180 to the firing switch 169, since, when the rammer is forward, the circuit will be through the contact 176 of the switch 173; thence through the lead 177 to the breech switch 145 which, when the gun is in battery, will be closed to carry the circuit through the lead 172 to the plunger 164 of the upper tray switch 163; and, the tray being up, the circuit will continue through the contact 166 of the switch 163 through the lead 168 to the firing switch 169. This same circuit, when complete, will illuminate the signal light 171. The gunner will thus be informed that the firing circuit is complete and may then close the switch 169 to the firing actuator 170 to fire the weapon. It will be noted that the remaining elements of the control mechanism are inactive and these have been illustrated in broken lines in Fig. 6.

Shell delivery (Fig. 7)

When the weapon recoils after firing, the driving member 66 on the breech ring 25 engages the shoe or cam 65 on the tubular support of the shell-feeding mechanism. Rocking of the cam in a counterclockwise direction (as viewed in Fig. 3) results in compression of the driving spring 73, and the spring-pressed latch 77 on the housing 68 drops in behind the plunger 69 and retains the spring 73 under compression. During this phase of operation there will be no change in the positions of the tray, feed screws, or sliding member 92 on the shaft 53.

At the beginning of recoil, the tube-and-breech assembly, by means of the driving plate 39 on the breech ring 25 and the buffer 40 on the rammer 30, picks up the rammer and drives it rearwardly to the position shown in broken lines in Fig. 2. As the rammer travels from its forward to its rearward position, the guide or control pin 34 follows the track 33 and, at the rearward end of the track, is caught and retained by the rammer latch 36. The gun will then return to battery under the action of its counter-recoil mechanism. While the rammer remains in its rearward position the plunger 178 of the switch 173 is released from the pressure of the control member 181 on the buffer 40 of the rammer and is thus permitted to make connection with the contact 174 of the switch 173. This action of the switch 173 breaks the circuit to the firing switch and initiates an electrical circuit that ultimately energizes the tray solenoid 114. However, this circuit will be complete only if: (a) the tray is up so that the plunger 159 is spring pressed outwardly to make an electrical connection with the

contact 157 of the switch 156; (b) the chamber 123 of the breech 25 is empty and the breech-block 26 is open, in which case the feeler switch 146 will be closed; (c) the gun is in battery so that the feeler switch will be operative; and (d) the rammer remains in its rear position so that the plunger 178 of the switch 173 is permitted to make connection with the contact 174. It will be noted in the foregoing statement of requirements that although the breech switch 145 is actually not in the circuit just established, nevertheless, the gun must have returned to battery; for, otherwise, the feeler switch 146 could not function. Further, it is to be understood that the gun includes the usual shell-extracting and ejection mechanism; however since the details thereof are not necessary to an understanding of the present invention, such structure has not been shown.

With the circuit complete, as shown in Fig. 7, the tray solenoid 114 is actuated and releases the release bar 122 from the upper catch 124 on the bracket 123, allowing the tray to descend by gravity, with a shell therein, to a position in which the shell is disposed in axial alignment with the breech of the gun and just forwardly of the rammer arm 31.

As the tray moves downwardly to shell-delivery position the sliding member 92 travels directly down the shaft 93 with the follower 98 of the sliding member following the straight groove 96 of the shaft. The driving spring 73 is still cocked or loaded and is still retained by the spring-pressed latch 77. Since the arm 76 on the cam 65 has been swung in a counterclockwise direction and retained there, it will have moved the connecting pin 70 to the left in the slots 72 of the housing 68, which action will have resulted in a generally vertical disposition of the connecting link 81. This positioning of the link 81 is permitted by the lost motion provided by the slots 86 and 87 therein. As the tray descends, the connecting links 89 and 113 will move the link 81 until it assumes a position generally parallel to the slots 72 and housing 68, and the pins 70 and 82 will be at the far ends of the slots 86 and 87, respectively. The linkage is thus prepared for returning the tray upwardly and for rotating the feed screws 51 and 53 when the latch 77 is released to permit reaction of the driving spring 73.

Ramming (Fig. 8)

As the tray assumes its lower or shell-delivery position, the forward tray arm 101 releases the plunger 164 of the switch 163 and the plunger 55 makes an electrical connection with the contact 165 to the tray solenoid 114. However, this circuit is inactive because of the position of the switch 173 (the rammer being in its rearward position). When the tray reaches its lower or 60 delivery position, the forward tray arm 101 positively engages the plunger 159 of the lower switch 156 and depresses the plunger to effect an electrical connection with the contact 158. Thereupon, the circuit through the lead 161 to the rammer solenoid 37 is completed, provided that at this time (a) the gun is still in battery, (b) the chamber 123 is still empty, (c) the rammer is still in rearward position and (d) the breech is open. Failure of any of these conditions to 70 occur will result in an incomplete circuit to the rammer solenoid 37. In other words, the rammer cannot ram a shell if the breech is closed, or if the gun is not in battery, or if a shell is already in the chamber, or if the tray has failed to descend completely to delivery position. The im-

portance of these preventive controls is illustrated by considering what would occur, if for example, the rammer rammed the shell when another shell was already in the chamber, particularly if the ammunition used was fuzed with point-detonating fuzes. In another example, if the tray was only part way down, the released rammer would engage the tray arms, thus damaging both the tray and the rammer.

When conditions are such that the circuit is complete to the rammer solenoid 37, this solenoid is energized and releases the latch 36 on the rammer housing 28 which in turn releases the pin 34 of the rammer 30 and allows the rammer to be rocked slightly (lowermost position of arm 31 in Fig. 10) and driven forwardly under action of the compression springs contained in the rammer housing extension 32. After the shell is chambered, the breech closes, there being provided in the gun the usual breech-closing mechanism. Since this mechanism is not necessary to an understanding of the invention, the structure and operation thereof have not been illustrated and described.

Shell advance (Fig. 9)

When the rammer reaches its forward position, the control member 181 on the buffer 40 engages and depresses the plunger 178 of the switch 173 and connects the source of energy 180 to the contact 176 of the switch 173. Since the gun is in battery, the battery switch 145 will be closed and the circuit will be carried to the upper tray switch 163. While the tray is down, in its lower or shell-delivery position, the plunger 164 of the upper switch 163 is in released position and an electrical connection is made with the contact 165, which completes the circuit to the tray solenoid 114 through the leads 160 and 161, whereupon this solenoid is energized and operates through the release bar 122 and release arm 123 to release the latch 77 on the driving spring housing 68. The release bar is simultaneously released from the lower catch 125 on the bracket 123.

Release of the tray for return to its upper position is made dependent upon return of the rammer to its forward position. The reason for this dependency will be clear when it is considered that if the tray began its upward travel before the rammer and shell cleared the tray, the result would be either damage to the tray and rammer or possible dislodging of the shell from its position.

When the latch 77 is withdrawn from behind the plunger 69 and the driving spring 73 reacts, the arm 76 (Fig. 3) is moved in a clockwise direction and, through the links 74 and 81 and links 89 and 113, drives the tray arms 101 and sliding member 92 upwardly. As the sliding member 92 is driven upwardly on the shaft 93, the follower 98 travels in the spiral groove 97, thus effecting one complete revolution of the shaft 93 and consequently of the feed screws 52 and 53. At the same time, the tray reaches or returns to its upper position adjacent the lower portions of the feed screws. As the feed screws rotate they feed or advance the next lowermost shell in the series to the now returned tray. When the tray leaves its lower position to move to its upper position the plunger 159 of the lower switch 156 is released from the pressure of the forward tray arm 101 and is spring-pressed to make electrical connection with the contact 157 of the switch 156 to again condition the tray solenoid 114 for

future action. Of present importance, however, is the fact that when the tray reaches its upper position it engages the plunger 164 which then breaks its connection to the contact 165 and makes connection with the contact 166, thus re-establishing the circuit shown in Fig. 6 and conditioning the firing switch 169 for action.

The importance of the preventive control consisting of the upper tray switch 163 and its relationship to the firing circuit is as follows: the tray must move upwardly and reach its upper position to engage the plunger 164 of the upper switch 163 for completion of the circuit through the contact 166 to the firing switch 169, since, if it were possible to fire the weapon with the tray in its lower or delivery position, or in any intermediate position, the tray would be seriously damaged by recoil of the tube-and-breech assembly.

It will be seen from the foregoing description that the objects of the invention hereinabove enumerated are simply and effectively achieved. Other objects of the invention will undoubtedly occur to those skilled in the art, as will several adaptations thereof. However, the invention has been illustrated and described in relation to only a preferred embodiment thereof and it will be understood that numerous alterations and modifications may be made in this preferred embodiment without departing from the spirit and scope of the invention as set forth in the appended claims.

I claim:

1. In combination, a gun having a tube-and-breech assembly mounted for recoil and return to battery, a support positioned in fixed relation to said gun, a rammer carried by said support for forward and rearward movement generally along a line paralleling the bore of said tube-and-breech assembly, means responsive to recoil of said assembly for moving said rammer rearwardly, means for releasably retaining said rammer in rearward position while said tube-and-breech assembly returns in counterrecoil, means for carrying a series of shells for said gun, means for delivering individual shells successively from said carrying means into the path of said rammer when the latter moves forwardly, first control means connected between said shell-delivering means and said tube-and-breech assembly and operable in response to return of said tube-and-breech assembly to battery to condition said delivery means for delivery of a shell to said rammer, second control means connected to the aforesaid rammer-release means and operable in response to the absence of a shell from said tube-and-breech assembly to partially condition said rammer-release means for release of said rammer, third control means also connected to said rammer-release means and operable in response to delivery of a shell to said rammer to complete conditioning of said rammer-release means to release said rammer, means for moving said rammer forwardly after release, and fourth control means connected to said shell-delivery means and operable in response to return of said rammer to its forward position for effecting operation of said shell-carrying means to advance of a shell to said shell-delivery means.

2. In combination, a gun having a tube-and-breech assembly mounted for recoil and return to battery, a support positioned in fixed relation to said gun, a rammer carried by said support for reciprocation generally along a line paralleling the bore of said tube-and-breech assembly,

means operated by recoil of said gun for moving said rammer rearwardly, means for releasably retaining said rammer in rearward position while said tube-and-breech assembly returns in counterrecoil, means on said support for carrying a series of shells for said gun, means for delivering individual shells successively from said carrying means to a position to be engaged and rammed by said rammer when the latter moves forwardly, control means for effecting operation of said shell-carrying means to advance shells successively to said delivery means, first control means connected between said shell-delivery means and said tube-and-breech assembly and operable when the latter has returned to battery to condition said delivery means for delivery of a shell into the return path of said rammer, second control means connected to the aforesaid rammer-release means and operable in response to movement of said delivery means to position a shell in the return part of said rammer, to thereby release said rammer, means for moving said rammer forwardly, and means connected to said shell-delivery means and operable in response to return of said rammer to its forward position for returning said shell-delivery means to initial position and simultaneously operating said shell-carrying means to advance a shell to said shell-delivery means.

3. In combination, a gun having a tube-and-breech assembly mounted for recoil and return to battery, means for carrying a series of shells for said gun, a support positioned in fixed relation to said gun, a rammer carried by said support for movement in a ramming cycle between a first position to receive a shell from said carrying means and a second position to chamber the received shell in the breech of said gun, means operated by recoil of said gun for moving said rammer to its first position, means for delivering individual shells successively from said carrying means to a position in the return path of said rammer when the latter moves from its first position to its second position, said shell-carrying means being operable to advance shells successively to said delivery means for delivery into the path of said rammer, first control means connected to said delivery means and to both said rammer and said tube-and-breech assembly and operable in response to both return of said tube-and-breech assembly to battery and movement of said rammer to its first position, to actuate said delivery means for delivery of a shell into the return path of said rammer, means in said tube-and-breech assembly for detecting the presence or absence of a shell therein, power means for moving said rammer to its second position, second control means connected to both said detecting means and said delivery means and operable in response both to the absence of a shell from said tube-and-breech assembly and to movement of said delivery means to shell-delivery position to actuate said power means for effecting movement of said rammer to its second position, and third control means associated with said shell-delivery means and operable in response to movement of said rammer to second position for returning said shell-delivery means to a position adjacent said shell-carrying means and simultaneously to actuate said shell-carrying means to deposit a shell in said shell-delivery means.

4. In combination, a gun having a tube-and-breech assembly mounted for recoil and return to battery, means for carrying a series of shells

for said gun, a support positioned in fixed relation to said gun, a rammer carried by said support for movement from a first position to a second position to chamber a shell in the breech of said gun, means responsive to recoil of said gun for moving said rammer to first position, means for delivering individual shells successively from said carrying means to a shell-delivery position in which the shells may be chambered by said rammer when the latter moves from its first position to its second position, first control means connected between said shell-delivery means and said rammer and operable in response to movement of said rammer to its first position to effect operation of said delivery means for delivery of a shell, power means for moving said rammer to its second position, second control means operable in response to movement of said delivery means to shell-delivery position for effecting movement of said rammer to its second position, and third control means operable in response to chambering of a shell by said rammer for moving said shell-delivery means to a position for receiving a shell from said shell-carrying means and simultaneously operating said shell-carrying means to effect advance of a shell to said shell-delivery means.

5. In combination, a gun having a tube-and-breech assembly mounted for recoil and return to battery, means for carrying a series of shells for said gun, a support positioned in fixed relation to said gun, a rammer carried by said support for movement in a ramming cycle from a first position to a second position to chamber the shell in the breech of said gun, means responsive to recoil of said gun for moving said rammer to its first position, means for delivering individual shells successively from said carrying means to a position to be chambered by said rammer when the latter moves from its first position to its second position, first control means including a switch operable in response to return of said tube-and-breech assembly to battery to effect movement of said delivery means to deliver a shell into the path of said rammer, power means for moving said rammer to its second position, and second control means including a switch operable by and in response to movement of said shell-delivery means to deliver a shell into the path of said rammer, to release said power means and effect movement of said rammer to its second position.

6. An automatic gun as recited in claim 5, said first control means comprising a circuit including said first-named switch and a third switch closed by and in response to initial movement of said shell-delivery means away from said shell-carrying means.

7. In an automatic gun having a tube-and-breech assembly mounted for recoil and return to battery, means for carrying a series of shells for said gun, a support positioned in fixed relation to said gun, a rammer carried by said support for movement in a ramming cycle between a first retracted position and a second position to chamber a shell in the breech of said gun, means powered by recoil of said gun for moving said rammer to its second position, means for delivering individual shells successively from said carrying means to a position in the path of said rammer when the latter moves from its first position to its second position, first switch means operable in response to both return of said tube-and-breech assembly to battery and movement of said rammer to its first position to cause said

delivery means to deliver a shell into the path of said rammer, means responsive to recoil of said gun for moving said rammer to its first position, and second switch means operable in response to movement of said shell-delivering means to deliver a shell into the path of said rammer to cause actuation of said rammer-moving means and thereby effecting movement of said rammer to its second position.

8. In combination, a gun having a tube-and-breech assembly mounted for recoil and return to battery, means for carrying a plurality of shells for said gun, a support positioned in fixed relation to said gun, a rammer carried by said support and mounted for movement between a first-retracted position and a second position to chamber the received shell in the breech of said gun, means for delivering individual shells successively from said shell-carrying means to a position in the path of said rammer when the latter moves from its first position to its second position, said shell-carrying means being operable to advance shells successively into the path of said delivery means for delivery to said rammer, a source of electrical energy, an electrical circuit connected to said source of energy and including a plurality of switches connected in series, the first of said switches being closed in response to movement of said tube-and-breech assembly to battery, the second of said switches being closed in response to movement of said rammer to its second position, and the third of said switches being closed in response to movement of said shell-delivery means to receive a shell from said shell-carrying means, and a firing control switch connected in series with the aforesaid switches in said circuit and operable to complete said circuit only when said first, second and third switches are closed.

9. In combination, a gun having a tube-and-breech assembly mounted for recoil and return to battery, means for carrying a plurality of shells for said gun, a support positioned in fixed relation to said gun, a rammer carried by said support and mounted for movement between a first position to receive a shell from said shell-carrying means and a second position to chamber the received shell in the breech of said gun, means for delivering individual shells successively from said shell-carrying means to a position to be received and chambered by said rammer when the latter moves from its first position to its second position, said shell-carrying means being operable to advance shells successively to said delivery means, a firing circuit for firing said gun, including a plurality of switches connected in said circuit, said circuit being closed to condition said firing control for operation only in response to movement of said rammer to its second position, of said tube-and-breech assembly to battery, and of said shell-advancing means to shell-delivery position.

10. In combination, a gun having a tube-and-breech assembly mounted for recoil and return to battery, means for carrying a plurality of shells for said gun, a support positioned in fixed relation to said gun, a rammer carried by said support for reciprocation in a path parallel to the bore of said gun between a rearward position to receive shells from said shell-carrying means and a forward position to ram a shell into the tube-and-breech assembly, means mounted on said shell-carrying means for movement from a first position remote from said tube-and-breech assembly to a second position generally in axial

alignment with the bore of said gun to deliver a shell to be received by said rammer in its rearward position, means associated with said tube-and-breech assembly for detecting the presence or absence of a shell therein, means for detecting the return or nonreturn of said gun to battery, means for moving said shell-delivery means to its second position and operable in response to the four conditions established by the disposition of said shell-delivery means in its first position, the absence of a shell from said tube-and-breech assembly, the disposition of said gun in battery, and the disposition of said rammer in its rearward position, means for moving said rammer to its forward position and operable in response to the four conditions established by disposition of said shell-delivery means in its second position, disposition of said gun in battery, absence of a shell from said tube-and-breech assembly and disposition of said rammer in its rearward position, and means for returning said shell-delivery means to its first position and operable in response to the three conditions established by the disposition of said shell-delivery means in its second position, the disposition of said gun in battery and the disposition of said rammer in its forward position.

11. In a gun having a breech mounted for recoil and return to battery and including a shell chamber and a breechblock movable for opening and closing, the combination with said breech of a support fixed against recoil, first and second actuatable elements on said support, a first control member on said breech and arranged to actuate said first element only when said breech is in battery, a second control member carried by said breech for movement with respect to said breech and said second element and arranged to be engaged and positioned by either a shell in said chamber or by said breechblock when closed for movement to a predetermined position with respect to said second element, and means for moving said second control member to a second predetermined position to actuate said second element when said chamber is empty and said breechblock is open.

12. In a gun having a breech mounted for recoil and return to battery and including a shell chamber, the combination with said breech of a support fixed against recoil, first and second actuatable elements on said support, a first control member on said breech and arranged to actuate said first element only when said breech is in battery, a second control member carried by said breech for movement with respect to said breech and said second element and arranged to be engaged and positioned by a shell in said chamber for movement to a predetermined position with respect to said second element, and means for moving said second control member to a second predetermined position to actuate said second element when said chamber is empty.

13. In a gun having a breech mounted for recoil and return to battery and including a breechblock movable for opening and closing, the combination with said breech of a support fixed against recoil, first and second actuatable elements on said support, a first control member on said breech and arranged to actuate said first element only when said breech is in battery, a second control member carried by said breech for movement with respect to said breech and said second element and arranged to be engaged and positioned by said breechblock when closed for movement to a predetermined position with

respect to said second actuator, and means for moving said second control member to a second predetermined position to actuate said second actuator when said breechblock is open.

14. In a gun having a breech mounted for recoil and return to battery and including a shell chamber and a breechblock movable for opening and closing, the combination with said breech of a support fixed against recoil, first and second actuators on said support and positioned at an upper portion of said breech, first control means on said breech and arranged for movement to a predetermined position with respect to said first actuator when said breech is in battery and to a second predetermined position when said breech is out of battery, second control means carried by said breech and including a control member mounted for vertical movement with respect to said breech into and out of a position obstructing said chamber and further obstructing movement of said breechblock to closed position, means for moving said control member to said obstructing position, said control member being movable out of obstructing position by a shell in said chamber or by said breechblock when closed, and means operatively associated with said second actuator and connected to said control member for movement thereby.

15. In a gun having a breech mounted for recoil and return to battery and including a shell chamber, the combination with said breech of a support fixed against recoil, first and second actuators on said support adjacent said breech, first control means on said breech and arranged for movement to a predetermined position with respect to said first actuator when said breech is in battery and to a second predetermined position when said breech is out of battery, second control means carried by said breech and including a control member mounted for movement with respect to said breech into and out of a position obstructing said chamber, means for moving said control member to said obstructing position, said control member being movable out of obstructing position by a shell in said chamber, and means connected to said control member for movement thereby and operatively associated with said second actuator.

16. In a gun having a breech mounted for recoil and return to battery and including a breechblock movable for opening and closing, the combination with said breech of a support fixed against recoil, first and second actuators on said support adjacent said breech, first control means on said breech and arranged for movement to a predetermined position with respect to said first actuator when said breech is in battery and to a second predetermined position when said breech is out of battery, second control means carried by said breech and including a control member mounted for movement with respect to said breech into and out of a position obstructing movement of said breechblock to closed position, means for moving said control member to said obstructing position, said control member being movable out of obstructing position by said breechblock when closed, and means connected to said control member for movement thereby and operatively associated with said second actuator.

17. In an automatic gun having a tube-and-breech assembly including a breechblock and mounted for recoil and return to battery, a rammer mounted adjacent said assembly for re-

ciprocation from a first retracted position to a second position to ram a shell into said breech, shell-delivery means operable to transpose a shell from a first station to a second station in the path of said rammer, shell-carrying means operable to support a series of shells for said gun and to convey the same, consecutively, to said first station and deposit the same in said shell-carrying means, means responsive to recoil of said gun to move said rammer to retracted position, releasable latch means holding said rammer in retracted position, a first solenoid energizable to release said latch means, spring means urging said rammer to second position, a first switch responsive to movement of said rammer into retracted position, a second switch responsive to movement of said breechblock to open position, a third switch responsive to movement of said shell-delivery means to said second station, and a circuit including a source of voltage, said first, second and third switches, and said solenoid, in series.

18. A gun as recited in claim 17, releasable dent means holding said shell-delivery means in said first station, a second solenoid carried by said shell-delivery means and energizable to release said dent means and permit said shell-delivery means to move to said second station, said third switch being a double-throw unit automatically moved to second position when said shell-delivery means is in said first station, and a second circuit including said source of voltage, said first and second switches, said third switch when in second position and said second solenoid in series.

19. A gun as recited in claim 18, said first switch being a double-throw unit automatically moving to a second position when said rammer is in its said second position, a fourth switch operable in response to movement of said assembly to battery, a fifth double-throw switch operable in response to movement of said shell-delivery means between said first and second stations, a second circuit to said second solenoid, and including said first switch when in second position, said fourth switch and said fifth switch when said shell-delivery means is in said second station, power means operable to return said shell-delivery means to first station, and means released by energization of said second solenoid through said second circuit, to release said power means and thereby effect return of said shell-delivery means to its first station.

20. In an automatic gun having a breech and a breechblock movable in said breech to open and close the same, a rammer reciprocable from a first to a second position to ram a shell into said breech, means powered by recoil of said gun to move said rammer to first position, releasable means holding said rammer in first position, a solenoid energizable to release said releasable means, a first switch closed by movement of said rammer out of said second position, a second switch closed by movement of said breechblock to open position, and a circuit including a source of power, said first and second switches and said solenoid, in series.

21. In an automatic gun having a breech and a breechblock movable in said breech to open and close the same, a rammer reciprocable from a first position to a second position to ram a shell into said breech, means responsive to recoil of said gun to move said rammer into said first position, means powered by recoil for urging said rammer into second position, releasable

23

latch means holding said rammer in first position, shell-carrying means, shell-delivery means operable between a first and a second position to convey shells, one at a time, from said carrying means into the path of said rammer, respectively, a first switch closed by movement of said rammer to said first position, a second switch closed by movement of said breech to open position, a third switch closed by movement of said shell-delivery means to second position, a solenoid effective to release said latch means, and a circuit including in series a source of power, said solenoid and said first, second and third switches.

22. In an automatic gun, having a breech and breechblock movable to open and close said breech, means for carrying a series of shells for said gun and operable to deliver the same one at a time to a first station, tray means operable to receive each shell at said first station and to convey the same to a second station for ramming into said breech, power means for moving said tray means from said second to said first station, latch means holding said tray means in first station, and releasing means carried by said tray means and operable to release said latch means when said tray means is in said first station and to effect operation of said power means when said tray means is in said second station.

23. In an automatic gun as recited in claim 22, second latch means holding said tray means in said second station, said releasing means being operable to release said second latch means at the same time it effects operation of said power means.

24. In an automatic gun having a breech and breechblock movable to open and close said breech, means for carrying a series of shells adjacent said breech and operable to feed said shells, one at a time, to a first station, tray means pivotable to receive each shell at said first station and to transpose the same to a second station for ramming into said breech, means including a spring, powered by recoil of said gun for pivoting said tray means from said second to said first station and simultaneously operating said shell-carrying means to feed a shell to said tray means when the latter arrives at said first station, first latch means holding said tray means at said first station, second latch means holding said spring in powered position, and solenoid-operated means carried by said tray means and operable to release said first latch means only when said tray means is at said first station, and to release said second latch means only when said tray means is at said second station.

25. In an automatic gun-loading mechanism, tray means pivotable on an axis parallel to the bore of a gun to transpose a shell from a first station to a second station in position to be rammed into a gun, a rod slideable on said tray means, a solenoid connected to slide said rod, a first latch engaged by said rod when said tray means is at said first station to hold the same

24

at said station, spring means operable to move said tray means from said second to said first station, a second latch holding said spring means against action, means carried by said rod and operable to release said second latch only when said tray means is at said second station, and circuit means including said solenoid, to energize the same.

10 26. A mechanism as in claim 25, a rammer movable from a retracted position to ram a shell from said tray means at said second station into said gun, a first double-throw switch operated by said rammer, said circuit means including a source of power and first and second branches, in parallel, each including a respective pole of said double throw switch.

20 27. A mechanism as covered by claim 26, said first branch including a second switch adapted to be closed by movement of the breech of said gun to open position and a third switch closed by movement of said tray means into said first station.

25 28. A mechanism as covered by claim 27, said second branch including a fourth switch closed by movement of said gun to battery.

29. A mechanism as covered by claim 28, said second branch also including a fifth double throw switch closed to one position by movement of said tray means into second station.

30 30. A mechanism as covered by claim 29, and a firing circuit for said gun including said source of power, said second branch and said fifth switch when closed to a second position by movement of said tray means out of said second station.

35 31. A mechanism as covered by claim 30, a third latch operable to hold said rammer in retracted position, a second solenoid energizable to release said third latch means, said third switch being a double throw unit moved into a second position by movement of said tray means to said second station, and a circuit for energizing said second solenoid and including said source of power, said first branch and said third switch when in its second position.

SIGMUND SCHIFF.
